UNITED STATES PATENT OFFICE.

GUSTAVE A. LEIMAN, OF NEW YORK, N. Y.

HOOD OF POLISHING AND BUFFING MACHINES.

1,375,303.

Specification of Letters Patent. Patented Apr. 19, 1921.

Application filed March 6, 1918. Serial No. 220,798.

To all whom it may concern:

Be it known that I, GUSTAVE A. LEIMAN, a citizen of the United States, and resident of the borough of Bronx, in the city and State of New York, have invented a new and useful Improvement in Hoods of Polishing and Buffing Machines, of which the following is a specification.

This invention relates to an improvement in hoods for polishing and buffing machines having novel means of applying light directly into the hood and upon the work being operated upon.

One of the objects is to provide a device which may be adjusted on the hood at different angles with respect to the operator and work.

Another object is to provide a device which is hinged to the hood and provided with a light holder arranged to be removed for cleaning and other purposes.

A practical embodiment of my invention is represented in the accompanying drawings in which,

25 Figure 1 represents a side view of one hood of a polishing and buffing machine with my improved device applied thereto, and a portion of the table being shown in section with a polishing head in position thereon.

30 Fig. 2 represents a front view of the same.

Fig. 3 represents a detail longitudinal section on a larger scale, taken in the plane of the line III of Fig. 2, looking in the direction of the arrow, and

35 Fig. 4 represents a horizontal section taken in the plane of the line IV—IV of Fig. 1, on a larger scale.

The table of the machine is denoted by 1 and has mounted thereon a polishing head 2 and a hood 3 having a mouth 4. The polishing head is provided with a spindle 5 having a buffing wheel 6 thereon, which is arranged in position in the mouth of the hood to deposit dust flying therefrom directly into the hood.

40 A shield 7 having side walls 8 is hinged at 9 to the upper part of the mouth 4 and arranged to swing toward and away from the mouth. The walls 8 are provided with radial rims 10 which have a slight yielding movement maintained by a spring wire 11 secured in the rims, the tension of which rims serves to keep the walls 8 and a beaded rim 12 on the mouth of the hood in intimate contact. To further insure the shield against unintentional displacement, I provide the

walls with a series of corrugations 13 which coact with the beaded rim 12. The wire 11 is extended beyond the radial rims 10 on the walls 8 to limit the outward movement of 60 the shield by its contact with the beaded rim 12.

The shield 7 has an opening 14 located centrally therethrough which is arranged to be covered by a light holder 15 having laterally extending tongues 16 which are arranged to slide in grooves 17 on the shield.

The holder 15 is provided with a socket 18 adapted to receive an incandescent lamp 19 and having a switch 20 for controlling the 70 lamp. The current is supplied to the lamp through a flexible cord 21 attached to a source of supply (not shown).

The inner wall of the holder 15 is furnished with a reflective surface to intensify 75 the power of the lamp in the hood.

The lamp 19 is protected from flying particles of dust and dirt by means of a wire mesh screen 22 secured to the shield in position to cover the opening 14.

80 Thus it will be seen that the light from the lamp may be reflected into the hood, the angle of which is under the control of the operator and may be adjusted to the position best suited to the work.

It is evident that various changes may be resorted to in the form, construction and arrangement of the several parts without departing from the spirit and scope of my invention and hence I do not intend to be limited to the details shown and described except as they may be specifically set forth in the claims.

What I claim is:

1. A hood for polishing and buffing machines having a shield pivoted thereon and provided with yielding side walls arranged to frictionally engage said hood for holding said shield in position with respect to the hood. 95

2. A hood for polishing and buffing machines having a mouth provided with a beaded rim, a shield pivoted at the upper side of the mouth and provided with yielding side walls arranged to frictionally engage said 105 rim for holding said shield in position with respect to the hood.

3. A hood for polishing and buffing machines having a mouth provided with a beaded rim, a shield pivoted at the upper side of 110 the mouth and provided with yielding side walls, said walls having a series of corruga-

tions arranged to frictionally engage said rim for holding said shield in position with respect to the hood.

4. The combination with a hood for polishing and buffing machines having a shield pivoted thereon and provided with yielding side walls arranged to frictionally engage said hood, said shield having an opening therethrough, of a lamp and holder slidably con-

nected to the shield in position to cover said opening and direct light into the hood and a screen covering the opening for protecting the lamp.

In testimony, that I claim the foregoing as my invention, I have signed my name this 15th day of March 1918.

GUSTAVE A. LEIMAN.
